UNITED STATES PATENT OFFICE

139,568

DESIGN FOR A CONDUIT SPACER

William H. D. Hinchman, Detroit, Mich.

Application September 16, 1944, Serial No. 115,323

Term of patent 14 years

(Cl. D26—1)

To all whom it may concern:

Be it known that I, William H. D. Hinchman, a citizen of the United States, residing at Detroit, in the county of Wayne and State of Michigan, have invented a new, original, and ornamental Design for a Conduit Spacer, of which the following is a specification, reference being made to the accompanying drawing, forming part thereof.

Fig. 1 is a side elevational view of a conduit spacer showing my new design, and

Fig. 2 is a perspective view thereof.

Both sides of the spacer are substantially the same.

I claim:

The ornamental design for a conduit spacer, substantially as shown and described.

WILLIAM H. D. HINCHMAN.
